UNITED STATES PATENT OFFICE

2,557,001

BOTTLE DISPOSAL RECEIVER

Alfred C. Kohl, Milwaukee, Wis., assignor to Kohl
Bottle Receiving Company, Milwaukee, Wis., a
partnership

Application November 26, 1945, Serial No. 630,802

3 Claims. (Cl. 198—47)

1

My invention relates to a bottle receiver for receiving empty bottles at a point of congestion and removing them to a receptacle located at a distance therefrom in which they may be temporarily accumulated and stored.

In the operation of taverns, soft drink establishments or the like, particularly during busy periods, a large number of empty bottles accumulate behind the bar, and clutter up the small space usually available, so that it is desirable to provide some means for removing the bottles, to prevent their accumulation, and to transfer them to a point some distance therefrom, where they may be collected and temporarily stored for subsequent sorting and disposal.

It is an object of my invention to provide a device whereby empty bottles may be transferred from a point of congestion, such as behind a bar or the like, to a receptacle located at a point some distance therefrom, as for example, in the basement beneath the bar, where the bottles may be collected and temporarily stored, to be later sorted and disposed of.

Another object of my invention is to provide a bottle handling device, which comprises a receiving device for the bottles located at one point, a collecting tray located at a more remote point, and a conveyor mechanism for transferring bottles from the receiving device to the collecting tray.

Another object of my invention is to provide a bottle handling device for transferring bottles from one point to another which is so constructed that the bottles will be handled without breakage.

Other objects and advantages will be apparent from the preferred form of my device, which is shown, by way of example, in the accompanying drawings, wherein:

Fig. 1 is a view showing my bottle receiver in elevation, with parts thereof broken away;

Fig. 2 is an elevation of a portion of my bottle receiver;

Fig. 3 is a view taken on line 3—3 of Fig. 1;

Fig. 4 is a section taken on line 4—4 of Fig. 3, to an enlarged scale; and

Fig. 5 is a section taken on line 5—5 of Fig. 3, to an enlarged scale.

My bottle receiving apparatus, which is illustrated in the drawings, comprises a bottle receiving tube 10, which is located back of a bar, or the like, from which a conduit or chute 11 extends beneath the floor 12 to a relatively large, generally horizontal, two-stage conveyor 13, at the other end of which there is provided a cylindrical receiving tray or collecting receptacle 14 and a small depositing conveyor 15. The empty bottles are dropped in the receiving tube 10, pass through the conduit 11 to the conveyor 13 and thence to the pivoted conveyor 15 and are collected in the receiving tray 14.

2

The bottle receiving tube 10, which is placed at the point where the bottles tend to accumulate, is provided with a top cover member 16, which is pivotally mounted thereon at 17 and connected, by means of a link 18, to a foot treadle 19. The U-shaped foot treadle 19 is pivoted at 20 to brackets 21 at the base of the tube 10. The operation of the foot treadle 19 pivots the top cover 16 about the pivot 17 so that empty bottles may be dropped therein.

An aperture 22 is provided in the floor 12 beneath the tube 10 and the chute 11 is connected in alignment therewith by means of the brackets 23, or the like, to provide a passageway 15 for the bottles. The chute 11 is curved so that the bottles are delivered on approximately a horizontal level, the lower end of the chute being supported on the hanger 24. The chute 11 may be of any appropriate material such as metal, rubber or the like which is sufficiently rigid and which will not result in breakage of the bottles as they pass through the same and the top of the curved portion of the same may be open. A stiff bumper gate 25 is pivotally mounted at 26 adjacent the discharge end of the chute 11 to arrest travel of the bottles at that point.

The endless conveyor 13 is provided with a horizontal portion 27 and a downwardly inclined portion 28, and comprises a canvas pocket member 29 supported between parallel rope members 30 by means of spaced metal straps 31. The parallel rope members 30 are supported on end pulley members 32 and 33. The upper pulley member 32 is supported in bearings 34 mounted on the hanger 24, thus locating the receiving end of the conveyor 13 beneath the discharge end of the chute 11. The path provided by the conveyor is changed from the horizontal direction to a downwardly inclined direction by means of guide pulleys 35 journaled on the hanger 24. A pivoted drag or flap 37 is provided on an extension 38 of the chute 11 to insure that the bottles are in a horizontal position on the conveyor 13 as they move away from the discharge end of the chute 11. At the point where the conveyor changes from the horizontal to the downwardly inclined path a curved cover or drag member 39 is pivoted at 40 to the hanger 36 to help keep the bottles on the conveyor. The discharge end of the conveyor is supported on the lower pulley members 33 which are mounted in spaced relation on a shaft 41 supported in bearing members 42 on the upright frame 43. A roller member 33' is rotatably mounted on the shaft 41 between the pulley members 33 and functions as a kicker for transferring the bottles from conveyor 13 to conveyor 15, as the conveyor members move around the pulley members 33.

At the discharge end of the conveyor 13 the

bottles are transferred to the receiving tray 14 by means of the conveyor 15, which comprises a frame, consisting of side plates 44 and end pulleys 45 and 46, the upper end of the plates 44 being rotatably mounted on the drive shaft 47 which is located adjacent the discharge end of the conveyor 13 and supported in the bearing brackets 48 mounted on the upright frame 43. The pulley 46 is journaled between the lower end of the side plates 44 while the pulley 45 is secured to the drive shaft 47. Carried on the pulleys 45, 46 are tapes 49 one of which has spaced fingers 50 thereon. The lower free end of the conveyor 15 is provided with a receiving platform 51 having a curved side rail 52 and a canvas apron 53. A counterweight 54 is mounted on the one end of a bar 55, pivoted at 56 on a bracket 57 which is supported on the top of the upright frame 43. A link 58 pivotally connects the other end of bar 55 to the plates 44 at 59 intermediate their ends. The free end of the conveyor is normally positioned adjacent the bottom of the receptacle 14. The counterweight arrangement is provided so that as the bottles accumulate in the receptacle and push up the free end of the conveyor 15 the latter will move upwardly without any appreciable resistance, and breakage of the bottles will be avoided. A curved guard member 60 is provided on the conveyor 15 to keep the tapes 49 free of bottles as they pile up in the receptacle 14.

The receptacle 14 is mounted on a shaft 61 which is provided with a bevel gear 62 cooperating with a bevel gear 63 on the laterally directed shaft 64 which carries a driving pulley 65 on its outer end. The shaft 64 is rotatably supported in bearing brackets 66 mounted on the platform or supporting frame 67. The platform 67 is connected at 68 to the vertical frame 43.

The endless conveyor 13, the transfer or depositing conveyor 15, and the rotatable receptacle 14, are all driven by means of a motor 69 provided with a pulley 70 which is connected by a belt 71 to the pulley 72 on the drive shaft 47. The drive shaft 47 is provided with a gear 73 cooperating with gear 74 on the shaft 41 to drive the pulley 33 and operate the conveyor 13. The shaft 47 is provided with a pulley 75 which is connected by a belt 76 to the pulley 65 to rotate the receptacle 14 by means of the shaft 64 and cooperating gears 62 and 63. The rotation of the shaft 47 operates the conveyor 15, pulley 45 being keyed to the shaft.

A switch 77 is provided on the bottle receiver 10 and is connected by means of a link 78 to the foot treadle 19. The switch 77 controls the starting and stopping of the motor 69, so that, upon depressing the treadle 19 to open the tube 10 for the reception of a bottle, the switch is operated to start the motor 69 and operate the drive mechanisms for the conveyors 13 and 15 and the receptacle 14. A tension spring 79 is provided to normally hold the foot treadle in inoperative position.

While I have referred to specific details of construction and materials in describing my device, it will be understood that other details of construction and other materials may be resorted to within the spirit of my invention.

I claim:

1. In a device of the type described, a bottle receiving tube having a pivoted cover member, a chute having a laterally extending end connected to the bottom thereof, an endless conveyor having a receiving end adjacent the dis-

charge end of said chute, said conveyor provided with a horizontal portion and a downwardly inclined portion, a rotatable receiving tray below the discharge end of said conveyor, a discharging conveyor having one end pivoted adjacent the discharge end of the downwardly inclined portion of said first conveyor and the other end vertically movably positioned above the receiving tray, drive means for operating the conveyors and rotating the receiving tray, switch means adjacent said bottle receiving tube for controlling the drive means, and treadle operated means adjacent said bottle receiving tube for operating said switch means and pivoting said cover member.

2. In a device of the type described, a generally vertical and normally closed bottle receiving tube, a chute connected to the bottom of said receiving tube and having a laterally extending lower end, an endless conveyor having a receiving end at the lower end of said chute, said conveyor provided with a horizontal portion and a downwardly inclined portion, a rotatable receiving tray below the lower end of said inclined conveyor portion, a discharging conveyor having one end pivoted adjacent the lower end of said inclined conveyor portion and the other end vertically movably positioned above said receiving tray, drive means for operating the conveyors and for rotating the receiving tray, switch means adjacent said bottle receiving tube for controlling said drive means, and manually operated means adjacent said bottle receiving tube for simultaneously opening said tube and operating said switch means.

3. In a bottle handling device, a generally vertical and normally closed bottle receiving tube, a bottle collecting receptacle located at a lower level and laterally spaced from said tube, means for conveying the bottles from said tube to said collecting receptacle comprising a chute having a laterally extending lower end connected to the bottom end of said bottle receiving tube, an endless conveyor having a receiving end adjacent the lower end of said chute, said conveyor having a downwardly inclined portion terminating adjacent the collecting receptacle, a discharge conveyor having one end pivotally supported adjacent the lower end of said endless conveyor, the free end of said discharge conveyor being movably positioned in the receptacle, said discharge conveyor being provided with a counterweight arranged to gradually raise the free end of the same as the bottles accumulate in said collecting receptacle, drive means for rotating said collecting receptacle and for driving said conveyors, a switch means for controlling said drive means and means at said bottle receiving tube for simultaneously opening said tube and operating said switch means.
